J. J. HIGGINS

MANUFACTURE OF INCANDESCENT ELECTRIC LAMPS

Filed Sept. 26, 1922

FIG. 1.

UNITED STATES PATENT OFFICE.

JOHN JOSEPH HIGGINS, OF EAST ORANGE, NEW JERSEY, ASSIGNOR TO WESTINGHOUSE LAMP COMPANY, A CORPORATION OF PENNSYLVANIA.

MANUFACTURE OF INCANDESCENT ELECTRIC LAMPS.

Application filed September 26, 1922. Serial No. 590,591.

This invention relates to machines for manufacturing incandescent electric lamps and relates more particularly to machines for sealing lamp mounts to bulbs.

5 An object of the invention is to provide an improved head for use with sealing-in machines in which a lamp mount and bulb may be united in a convenient and expeditious manner.

10 Another object is to automatically discharge cullets from the head after the sealing operation.

A further object is to provide coordinating machine elements which will automatically adjust a lamp bulb and mount in a given relation and secure and subsequently discharge the cullet after the sealing-in operation.

Other objects will be apparent from the 20 following description.

Machines for sealing mounts to bulbs are well known in the art, a preferred commercial machine being of the planetary type which comprises a rotatable carrier or conveyor upon which are mounted rotatably, a plurality of sealing-in heads. The heads employed in these machines usually have a means for supporting a bulb and other means for securing and holding a lamp mount 25 which mount includes such parts of the lamp as subsequently constitute its internal structure.

In the manufacture of tipless lamps, the mount includes an exhaust tube which projects from the lamp after the sealing-in operation and provides a communicating passage whereby the bulb may be exhausted.

When a bulb and mount have been properly disposed in a head, the head is carried 40 to a position for the application of heat which is supplied by means of fires, termed forming fires, which heat a portion of the bulb adjacent to the flare on the mount. At the same time, a downwardly acting force is applied to the lower end of the neck of the bulb, thus effecting an elongation of the plastic portion to bring the sides thereof 45 in contact with the edge of the flare to effect a seal between the mount and the bulb, after which, cutting off fires sever the cullet

from the sealed-in lamp. Before the bulb is removed from the machine and while the seal is still in a plastic state, the mount is pulled down a slight amount to produce a stretching and thinning of the glass at the 55 seal for the purpose of avoiding certain strains which may otherwise be caused during subsequent changes in temperature.

In many machines heretofore employed, the cullet usually remains attached to some 60 portion of the head, and is often left hanging upon the mount support. It is then necessary for the operator to either lift the cullet over the upper end of the mount support or to break the cullet and thus remove it. 65

Furthermore, heads as heretofore constructed have required the manipulation of one or more levers to operate jaws for gripping the bulb, and the supporting structure for such jaws has been disposed on at least 70 two sides of the head. This necessitated the exercise of a certain amount of caution on the part of the operator to avoid personal contact with these parts when assembling the bulb and mount. It will be readily appreciated that the speed of assembling the 75 mount and bulb was thereby retarded, since the structure about the lamp becomes extremely hot and interferes with the movement of the operator.

The above disadvantages are overcome in the present invention which provides a means for gripping and discharging a cullet. The gripping means are of such construction that the cullet may be gripped by jaws 85 without any manipulation of levers by the operator. Moreover, my improved head is free from structural elements or parts which may interfere with the movements of the operator, and a bulb and mount may, therefore, be positioned in proper relation without retardation of speed on the part of the operator.

A machine embodying my invention may consist of a sleeve in which is disposed a reciprocal member or shaft having its lower end in contact with a cam surface and provided with a chuck or mount-holder at its upper end to receive and secure an exhaust tube of a lamp mount. A suitable bulb- 100

support may also be provided for holding a bulb in proper relation to a mount when secured in the chuck.

Spring-actuated jaws are provided to receive the lower end of a bulb which is subsequently separated from the sealed-in lamp and becomes the cullet or surplus material which must be discharged from the head. These jaws automatically snap over the lower edge of the bulb-neck when a slight pressure is exerted thereon and they may operate to grip the neck to aid in maintaining the bulb in a given position during the sealing-in operation. After the sealed-in lamp, consisting of a bulb, and mount consolidated therewith, is removed, the cullet remains secured by the jaws. The head may then be moved by the usual conveyor, and certain machine elements operate to lower the mount support and release the jaws to discharge the cullet, which may then be carried away by any suitable guide or chute.

The invention will be more clearly understood by reference to the drawing in which;

25 Fig. 1 is a front view, in elevation, of my improved head, partly in section;

Fig. 2 is a side view, in elevation, of the head, partly in section;

30 Fig. 3 is an enlarged plan view of the jaws for securing the cullet, the portion in section being taken on line III—III in Fig. 2;

Fig. 4 is a front elevation of the jaws shown in Fig. 3;

35 Fig. 5 is a view taken on line V—V of Fig. 2; and,

40 Fig. 6 is a diagrammatic representation of the relation of the contacting parts of the stem head and the cam surface which operates certain elements of the head.

As illustrated, my head may include a central spindle 10 movable vertically within a sleeve 11 and having its lower end normally engaged by the surface of a cam 12. 45 The upper end of the spindle 10 is provided with a collar 13, suitably attached thereto. Extending upwardly and fastened to this collar, is a tubular member 14 provided with a plurality of apertures 15 (preferably 50 three) disposed circumferentially in the wall thereof and positioned in a common horizontal plane.

In each of the apertures 15 is disposed a spherical member or ball 16. Other balls 17 are disposed in apertures 18 disposed similarly to the apertures 15 but in a higher plane. The balls 16 and 17 are adapted to engage and secure an object, such as the exhaust tube 19 of a mount, when the same is 60 inserted, as shown in dotted lines, into the member 14. The balls are normally urged toward the axial line of the member 14, by reason of their contact with an inner tapered surface 20 of a thimble or cap 21, which may 65 be normally free to descend to make contact

with and move the balls 16 and 17. The apertures in which the balls are disposed are of slightly less diameter than the diameter of the balls; therefore, the balls are prevented from passing entirely into the tubular 70 member 14.

Although the above described means for securing an exhaust tube of a mount has been found preferable, it is to be understood that any suitable form of chuck may be employed.

The sleeve 11 is movable vertically in a bushing 22 which is rotatably disposed in a hub 23 of a conveyor 24. The bushing 22 is secured against downward movement by 80 a collar 25 which is tightly fitted to the upper end thereof. The lower end of the bushing has secured thereto a driving pulley or sheave 26 which may be rotated by means of a belt connection with driving mechanism of any suitable type. Such mechanism is well known and, therefore, not shown in the drawing.

85 A ball bearing 27 may be disposed between the upper end of the hub 23 and the collar 25 to reduce friction. The collar 25 is provided with an arm which terminates in a support 28 in which a tubular upright 29 is secured. Movable positioned within the upright 29 is a plunger or support rod 30, the upper end of which is secured to an extension or counter balance portion 32 of a bulb-support 33; thus, the bulb-support is movable with the rod 30. The bulb-support 90 preferably consists of a plurality of suitably positioned arms 34, the ends of which provide a plurality of surfaces for seating a bulb 40 when placed within the support.

95 The upper portion of the bulb is thus adjusted and retained, and the lower portion of the bulb may be gripped by a pair of jaws 35 and 36 carried on arms 37 and 38. The arms 37 and 38 are pivoted on pins 39 and 41 which are suitably fastened in projections 42 and 43 integral with a collar 44, connected to the tubular member 29. The jaws 35 and 36 are provided with suitable offset bearings 45 and are pivoted to lugs 46, integral with arms 37 and 38, by pintles 47. Suitable springs 48 are provided to urge the 105 jaws toward the vertical axis of the head. The jaws 35 and 36 are adapted to be separated by the insertion of an end or the neck of a bulb and to then grip the neck until it is automatically removed.

110 The arms 37 and 38 are normally maintained in given positions by means of springs 49 and 51 which have corresponding ends in constant engagement with the arms to normally urge them to such positions as to cause the jaws 35 and 36 to properly grip a cullet. Set screws 52 and 53 provide for the proper adjustment of the jaws to vary their positions in accordance with the diameter of the cullet of a bulb.

An opening of the jaws is effected by a positive means which may comprise a V shaped wedge-member 54 which is secured to a slideable collar 55 movable longitudinally of the upright 29 and retained from rotary movement by a feather 56 secured in the upright. The wedge-member or spreader 54 is normally positioned above beveled edges 57 of the arms 37 and 38 so that a downward movement of the member 54 will cause a separation of the arms. The spreader is, however, normally held above the arms by a spring 58 disposed between the collar 55 and the collar 44. The spring 58 acts normally to force the collar 55 upwardly against a stop plate 59 which is secured to the upper end of the upright 29. Thus, the spreader is adapted for vertical movement but is normally held in a given position above the arms 37 and 38.

The rod 30 is provided with a transverse pin 60 which projects from opposite sides of the rod and, when it is moved downwardly, the pin 60 passes through slots 61 in the plate 59 and slots 62 in the upright 29 and makes contact with the collar 55. A downward movement of the spreader may thus be caused to effect separation of the arms 37 and 38 and thus remove the jaws 35 and 36 from engagement with a cullet. The rod 30 is reciprocated with each reciprocation of the sleeve 11, being connected thereto by means of a bracket 63, to which the rod 30 is secured by pin 64, the pin 35 being movable in a slot 65 in the upright 29.

The bracket 63, secured to the upper end of the sleeve 11, is provided with a set screw 66, one end of which is disposed in a slot 67 provided in the shaft 10, thus preventing relative rotary movement of the shaft and permitting a slight vertical movement thereof within the sleeve 11.

After a mount and a bulb have been positioned in the head, the head may be rotated, by the conveyor 24, to a position at which a heat zone is created by suitable forming fires 68, indicated in dotted lines, which soften the bulb to a given degree. The head may then move to another station, during which time it reaches an ascending portion of the cam 12 hereinafter more fully described, which operates to raise the spindle 10 and the sleeve 11, thereby raising the bulb and mount. The jaws, however, remain stationary and, since the jaws grip the lower end of the bulb, the bulb is stretched and contact is made between the sides thereof and the flared portion of the mount to produce a union between the mount and the bulb.

To release the exhaust tube, secured by the balls 16 and 17, a slight downward movement of the rod 10 is produced. This is accomplished, during the rotary movement of the head with the conveyor, by means of

suitable undulations in the surface of the track 12 which may have a descending slot to permit a drop of the spindle 10. The sleeve, however, may be maintained in its given position by contact with the surface 12 at the sides of the slot.

The initial downward movement of the spindle 10 may effect a downward movement of the mount within the bulb immediately after the sealing operation is performed and while the material is still in a plastic condition. This slight downward movement is termed the pull-down and may be of any desired length. A more detailed description of the cam 12 and its cooperative relation to the sealing-in head will be given below.

It will be noted that, as the spindle moves downwardly, the distance of the pull-down is governed by the distance between the lower end of the cap 21 and the upper surface of the arm 63. Thus, when the spindle 10 moves downwardly and the cap engages the arm 63, the movement of the cap is terminated, and a slight continuation of movement of the spindle causes the balls to release the exhaust tube 19, thus leaving the bulb free for removal by an operator. After a mount has been sealed to a bulb, the cullet is, however, still secured between the jaws 35 and 36 and, as the conveyor is advanced the sleeve 11 and spindle 10 move from contact with the cam surface and descend as hereinafter more fully described. Thus, the rod 30 and the bulb-support 33 are moved downwardly, as well as the mount holder, and the pin 60 engages the collar 55 to cause the spreader 54 to separate the arms 37 and 38 and release the cullet from between the jaws 35 and 36. For the purpose of positively effecting a removal of the cullet and to prevent its direct downward movement, a pair of deflector members or fingers 71 are provided in the form of vertical rods having offset portions disposed in the normal downward path of the cullet. The rods are positioned in suitable apertures in the arms 37 and 38 and may be adjusted by means of set screws 72. After the cullet has been removed, the mount holder and bulb support are returned to loading positions by reason of the form of the cam surface, and another mount and bulb may be applied to the head.

Suitable laterally disposed cam surfaces 73, as indicated in dotted lines in Fig. 1, are provided in the usual manner to terminate the rotation of the head at certain stations. The cam surfaces may be so disposed that, when the head takes a given position during its course of travel with the conveyor, a pin 74 engages the cam 73 and terminates the rotation of the head, at which time the pulley 26 may be removed from the driving means or may be so connected thereto by a

loose belt that the belt will slip and not be effective during certain periods throughout the movement of the conveyor.

Since mechanism for performing the operation just mentioned, is well known, it is believed that further description is unnecessary. It is also obvious that, if desirable, the spindle 10 may be hollow and, at given stations throughout its travel over the surface of the cam 12, may be disposed in communication with a suitable passage way through which air may be forced upwardly through the spindle and through the chuck to supply air jets to the lower end of the flare tube during the sealing-in operation. This is also well known in the art, and therefore, need not be further described.

The operation of the head will be more fully understood from the following general description, taken in connection with Fig. 6 which shows a diagrammatic representation of the cam surface 12 and the several undulations of the surface thereof for operating the spindle 10 and the sleeve 11.

At the first or loading station, the cam 12 is provided with a slot 75 into which the spindle 10 may drop. The sleeve 11 is, however, maintained in its normal position by reason of its contact with the upper surface 76 of the cam 12. The lowered position of the spindle 10 will cause the cap 21 of the mount holder to engage the upper surface of the arm 63 and thereby open the chuck for the admission of an exhaust tube.

Assuming that the conveyor carries the head in the direction of the arrow "A", it will be understood that, as the head moves to the next station, the spindle 10 rides up the surface of the slot 75 until it travels along the upper surface 76 of the cam 12, at which time the cap 21 will be lifted, and the balls 16 and 17 of the chuck will make contact with the inner surface of the cap and engage the exhaust tube to secure a mount in position on the holder. A bulb may then be placed over the mount and seated in the bulb-support member 33. The conveyor is then permitted to rotate to subject the bulb to the forming fires which are located at suitable stations throughout the path of movement of the head.

As the head approaches the next-to-the-last station, an ascending portion 77 of the cam 12 causes an upward movement of the spindle 10 and the sleeve 11, with a consequent elongation and reduction in diameter of the portion of the bulb which has been heated to seal it to the mount, and suitable cutting-off fires subsequently operate to sever the lower end or cullet from the bulb. The head may then be moved until the spindle 10 enters a slot 78 in the cam 12; thereby releasing the exhaust tube from the chuck. A continued movement of the conveyor then brings the spindle 10 and

sleeve 11 entirely from engagement with the cam 12 which results in a downward movement of the bulb-support and the mount holder. The pin 60 is disposed in the rod 30 to permit the upper end of the mount holder to pass below the lower edge of the cullet just previous to the engagement of the pin 60 with the collar 55, which will then cause a downward movement of the spreader 54 and an opening of the arms 37 and 38, with a consequent discharge of the cullet. As the conveyor is then moved, the spindle 10 and the sleeve 11 again move upwardly, by reason of their contact with an ascending surface 79 of the cam 12; and the bulb-support, and the mount holder again takes the position indicated for the first or loading stage.

From the foregoing it will readily be appreciated that a semi-automatic sealing-in head is provided in which all the operating elements are so disposed as to be in the rear of the work parts and removed from interference with the movements of the operator when assembling or removing the work parts. In this improved head, it is not necessary for the operator to handle or manipulate any levers or other controlling mechanism in the vicinity of the head itself, thereby avoiding the possibility of personal contact with a heated projecting structure.

Although I have shown only a preferred embodiment of my invention, it is obvious that modifications may be made therein without departing from the spirit and scope of the appended claims.

What is claimed is:

1. A head for a sealing-in machine comprising a bulb support, a mount support, pivoted jaws for gripping a cullet, means for changing the relative positions of said jaws and said supports and means for automatically opening said jaws.

2. A sealing-in head comprising a bulb-supporting member, a mount-supporting member, oscillatory jaws for securing the lower portion of said bulb, means for severing said lower portion from said bulb and means for automatically discharging said severed portion.

3. A sealing-in head comprising a bulb-support a mount-support, oscillatory jaws for gripping the lower end of a bulb, positioned in said bulb-support, means for heating said bulb, means for changing the relative positions of said bulb-support and said jaws to elongate said bulb.

4. A sealing-in head comprising a bulb-support, a mount support, means for gripping the lower end of a bulb positioned in said bulb-support, means for locally heating said bulb, means for changing the relative positions of said bulb-support and said gripping means to elongate said bulb, means for

severing the lower end of said bulb and means for discharging said end from the head.

5. A sealing-in head comprising a bulb-support, a mount-support and a cullet-gripping member comprising a pair of independently pivoted jaws, means for locally heating a bulb disposed in said bulb-support, means for changing the relative positions 70 of said member and said supports to elongate said bulb, means for severing the cullet from said bulb and means for automatically separating said jaws to release a cullet.
6. A sealing-in head comprising a bulb-support, a mount-support and a cullet-gripping member comprising a pair of jaws, means for locally heating a bulb disposed in said bulb-support, means for changing the relative positions of said supports and 80 said member to elongate said bulb, means for severing the cullet from said bulb and means for actuating said jaws to discharge said cullet.
7. A sealing-in head comprising a bulb-support, a mount-support and a pair of cullet-gripping jaws, means for locally heating a bulb disposed in said bulb-support, means for sealing said bulb to a mount in said mount-support, means for changing the 90 position of said mount with respect to said bulb, means for severing the cullet portion of said bulb and means for discharging said cullet.
8. A head for a sealing-in machine comprising a bulb-support, a mount-support and a pair of oscillatory arms, movable jaws carried on said arms for gripping the end of a bulb means for severing the end from the bulb and means for automatically operating 100 said arms to release said end from said jaws.
9. A head for a sealing-in machine comprising a bulb-support, a mount-support and a pair of oscillatory arms provided with jaws for gripping an end of a bulb, means for severing said end from said bulb and means for automatically discharging said end from said head.
10. A head for a sealing-in machine comprising a bulb-support, a mount-support, a pair of movable jaws mounted on oscillatory arms for gripping an end of a bulb positioned in said bulb-support, means for heating said bulb, means for changing the relative positions of said jaws and said supports 110 to effect a seal between a mount in said mount-support and said bulb, means for severing the lower end of said bulb and means for operating said jaws to discharge said severed end.
11. A head for a sealing-in machine comprising a bulb-support, a mount-support, a pair of oscillatory arms provided with jaws for gripping the end of a bulb positioned in said bulb-support, means for locally heating 120 the bulb, means for changing the relative position of said bulb and a mount positioned in said mount-support to relieve strains at the seal between said bulb and said mount.
12. A head for a sealing-in machine comprising a bulb support, a mount support to hold a mount on the axial line of a bulb positioned in said support, means for gripping an end of a positioned bulb, means for locally heating the bulb, automatic means for causing a relative movement between said bulb support and said gripping means, 75 means for severing the cullet from the bulb and means for automatically discharging the cullet.
13. A head for a sealing-in machine comprising a bulb-support, a pair of oscillatory arms provided with jaws for gripping an end of a bulb positioned in said support, means for locally heating said bulb, means for raising said support to elongate said bulb, means for severing said end from said bulb, means for actuating said jaws to release said end and means for deflecting said end from its normal path of movement.
14. A head for a sealing-in machine comprising a bulb-support, a mount-support and a pair of oscillatory arms provided with jaws, means for gripping the neck of a bulb positioned in said support, means for locally heating said bulb to seal a mount thereto, 95 means for severing the cullet from said bulb, means for changing the position of said mount with respect to said bulb and means for automatically discharging said cullet.
15. A head for a sealing-in machine comprising a bulb-support, a mount-support and a pair of jaws for gripping the neck of a bulb positioned in said bulb-support, means for locally heating the bulb, means for moving said bulb-support upwardly to elongate 100 said bulb and cause a union between the walls thereof and a mount positioned in said mount-support, means for severing said neck of the bulb, means for moving said mount-support downwardly with respect to the bulb and means for discharging the severed neck.
16. A head for a sealing-in machine comprising a bulb-support, a mount-support and a pair of jaws for gripping the neck of a bulb positioned in said bulb-support, means for locally heating the bulb, means for moving the bulb-support downwardly to elongate the heated portion of the bulb, means for severing the cullet from the bulb and means for changing the relative position of said bulb and a mount positioned in said mount-support to relieve strains at the seal between said bulb and said mount.
17. A head for a sealing-in machine comprising a bulb-support, a mount-support and a pair of jaws for gripping the neck of a 130

bulb positioned in said bulb-support, means for locally heating the bulb, means for moving the bulb-support downwardly to elongate the heated portion of the bulb, means for severing the cullet from the bulb, means for changing the relative position of said bulb and a mount positioned in said mount-

support to relieve strains at the seal between said bulb and said mount and means for automatically discharging the cullet.

In testimony whereof, I have hereunto subscribed my name this twenty-fifth day of September, 1922.

JOHN JOSEPH HIGGINS.
